FROZEN CONFECTION

Martin J. Ferguson, 44 Summer Road,
Greenwich, Conn. 06830

Filed Oct. 11, 1967, Ser. No. 8,955

Term of patent 14 years

U.S. Cl. D1—5
Int. Cl. D1—01; D1—02

FIG. 1 is a front perspective view of a frozen confection showing my new design;

FIG. 2 is a top plan view thereof;

FIG. 3 is a bottom plan view;

FIG. 4 is a front elevation; and

FIG. 5 is a side elevation thereof.

Front and back as well as opposite sides are substantially identical.

I claim:

The ornamental design for a frozen confection, substantially as shown and described.
